UNITED STATES PATENT OFFICE.

JOHN F. KELLY, OF PITTSFIELD, MASSACHUSETTS.

EXPRESSION-CONTROLLING MEANS FOR MUSICAL INSTRUMENTS.

1,103,590.

Specification of Letters Patent. Patented July 14, 1914.

Application filed April 22, 1907. Serial No. 369,520.

To all whom it may concern:

Be it known that I, JOHN F. KELLY, a citizen of the United States, residing at Pittsfield, county of Berkshire, and State of Massachusetts, have invented certain new and useful Improvements in Expression-Controlling Means for Musical Instruments, fully described and represented in the following specification and the accompanying drawings, forming a part of the same.

This invention relates to automatically operated musical instruments, and more particularly to a method and means for producing desired expression in the production or rendering of a musical composition by such automatically operated instruments by varying the strength or loudness of the different tones which go to make up the composition.

Although the invention in some of its features may be employed for determining the loudness with which the piece or composition as a whole is played or for determining the relative loudness of notes played in succession, yet the invention is intended more particularly and in some of its features relates especially to the emphasizing of one or more of a plurality of simultaneously sounded tones for the purpose of enabling the theme or melody to be brought out distinctly above the accompaniment.

In accordance with the present invention, the actuating devices and, therefore, also the tone producing devices of the musical instrument are grouped so as to avoid the necessity of extreme subdivision and at the same time enable the desired effects to be readily produced, and this result is obtained by grouping or connecting together devices corresponding to tones which are in consonance, that is, instead of grouping or connecting together devices corresponding to a plurality of successive tones in the scale, or in the case of the piano or other keyboard instrument, tones the operating keys for sounding which are arranged together, the actuating or tone producing devices corresponding to tones of the same note name are grouped or connected together, so that the devices corresponding to the A tones, for example, will be in one group, devices corresponding to the A# tones in another group, devices corresponding to B tones in another, and so on.

In the class of musical instruments or playing apparatus therefor to which the in-

vention mainly relates, the sounding of the tones is controlled by a so-called music sheet or record sheet in which the various notes are represented by suitable actuating or controlling devices, usually perforations, the position of which transversely of the sheet determines the particular tone to be sounded, and lengthwise of the sheet the time and order in which the successive tones are to be sounded. When the groups above referred to are to be controlled automatically for the purpose of emphasizing individual tones, they are controlled in accordance with the invention by controlling devices which in turn are controlled through the medium of special perforations or other devices on the music sheet, and in connection with such automatic control there are also preferably provided suitable finger keys or other means for actuating or controlling such controlling devices arbitrarily or at will.

The invention relates in some of its features, especially to electrically-operated sheet-controlled playing apparatus for pianos or other musical instruments and more especially to apparatus of this kind in which the tone producing devices of the piano or other musical instrument are actuated directly by the operation of suitably connected electromagnets, and the invention has been made more particularly with the idea of providing expression controlling means and especially means for emphasizing individual notes in an automatic playing apparatus corresponding in its general structure and operation to that shown in United States Patent No. 753,809, granted March 1, 1904, for improvements in automatic playing apparatus for musical instruments, on the application of T. B. Powers and M. R. Jewell. Instead of resorting to the use of resistance changing devices for changing the magnetomotive force of the operating magnets in instruments of the character disclosed in said Patent No. 753,809, or in addition to, or as supplemental of, the expression-controlling system employing such resistance devices, the magnetomotive force of the operating magnets is varied in accordance with the present invention by changing the impressed electromotive force of the magnet circuits. Among other advantages of this method of controlling the strength of the operating magnets, is that a group of magnets may be controlled through the operation of a single

circuit controlling device or switch. To provide for emphasizing individual tones, the operating magnets are grouped or connected in the manner already pointed out according to the consonance of the tones which are to be produced through the action of such magnets, so that the desired tone or tones may be emphasized above others sounded simultaneously therewith by increasing the impressed electromotive force of the circuits to the magnets of the particular group or groups corresponding to the tone or tones to be emphasized. The circuits or branches leading to all the magnets of a group may thus be controlled by a single circuit controlling device or switch, whereas if resistance changing devices were depended upon for changing the magnetomotive force of a group of magnets it would be necessary to provide a separate coil and contact for the circuit or branch leading to each magnet. This feature of the invention of varying the magnetomotive force of the operating magnets by changing the impressed electromotive forces of the magnet circuits is not to be limited, however, to use in a system of expression control in which the magnets are permanently grouped in the manner stated, as this method of effecting a change in the magneto-motive force by means of a note-sheet having a single row of accent perforations for controlling the closure of the circuits of the magnets may be employed with other systems of grouping or when the desired control of the circuits is secured without resorting to any system depending on permanent groups; and, on the other hand, the grouping of the operating magnets in instruments of the character disclosed by said Patent No. 753,809 according to the consonance of the tones to be sounded is not in its broader aspect to be limited to a system in which the changing of the magneto-motive force of the magnets is effected by changing the electromotive force of the currents impressed on the magnet circuits.

I am aware of the German patent to Schubbe No. 180,649, dated January 29, 1907, which shows broadly a system of accenting by varying the voltage of the current impressed on the operating magnets, but my present invention differs therefrom in two important particulars, namely—in the use of a single electromagnetic-switch for opening one circuit and closing another in the connections from the operating-magnets to different potential points of the source of electrical energy; and second in the use of a perforated note-sheet having a single line of perforations for controlling the connections to the electro-magnetic switch.

The method of changing the operating strength of the operating magnets by chang-

ing the electromotive force of the currents impressed on the magnet circuits may also be employed for simultaneously increasing or decreasing the loudness with which the music as a whole is rendered or the relative loudness of successive tones, by providing suitable connections for effecting the necessary change in the impressed electromotive force of the circuits leading to all the key actuating magnets, and means for doing this may be combined with means for effecting the emphasizing of the individual tones.

A full understanding of the invention can best be given by a detailed description of a complete system providing for both automatic and manual control, and such a description will now be given in connection with the accompanying drawings which shows so much as is necessary for an understanding of the invention of an automatic playing apparatus similar to that shown in said Patent No. 753,809, provided with controlling devices and electrical connections for giving complete expression control in accordance with the present invention.

In said drawings, Figures 1 and 1^a illustrate diagrammatically an application of the present invention to an automatic playing apparatus similar to that shown in said Patent No. 753,809, only such parts of the playing apparatus and electrical connections being shown as are required to enable the present invention to be clearly illustrated. Fig. 2 shows a portion of a perforated music sheet intended for use in an instrument constructed in accordance with diagrams Figs. 1 and 1^a, and Fig. 3 is a similar view of a portion of a perforated music sheet for causing the same music to be played in the apparatus of said Patent No. 753,809. The same music is also written or represented on the sheet with Figs. 2 and 3 according to the usual system of musical notation. Fig. 4 is a detail horizontal plan view of the double-circuit controlling switch, the section being taken slightly below the upper surface of the insulating disk to which the contact plates are secured.

Referring to Figs. 1 and 1^a, these figures show at the top a series of finger keys 2 representing the keyboard of a piano. These keys are arranged in the usual manner in successive series of seven natural or white keys for striking the A, B, C, etc., to G tones, and with the sharp or black keys for striking the A#, C#, D#, F# and G# tones arranged between the proper natural tone keys. The key operating magnets 3 are located beneath the keyboard, there being in the actual apparatus a magnet for each key. The diagram, to avoid confusion of parts, shows only the magnets for operating the A and A# keys. These magnets as shown are of the two-pole form having

a pivoted oscillating armature 11 mounted between the poles and the armature of each magnet being connected with the underside of its corresponding key by connecting rods 12 and 13, whereby when any magnet is energized and its armature rotated the key with which the armature is connected will be drawn downward to cause the operation of the corresponding tone producing device 10 of the piano. The connecting rods 12 and 13 are connected together in the manner shown and described in said Patent No. 753,809 so as not to interfere with the manual operation of the finger keys of the piano. Each 15 of the key operating magnets 3 is electrically connected with a contact device of the controlling or transmitting mechanism through which connection may be made with one pole of a battery 10 or other suitable 20 source of electrical energy, and each is connected with a wire 6 which connects with the other pole of the battery, the magnets being thus located each in an independent branch circuit controlled by a contact device 25 forming part of the transmitting or controlling mechanism.

The transmitting or controlling mechanism, as shown, comprises a series of contact fingers or rods 32 adapted to make contact with a sectional contact bar 31 and normally held out of engagement with the sections of the bar 31 during the operation of the instrument by means of rocking fingers 37 which are controlled for causing or permitting the contact fingers to make contact with the bar 31 by means of a perforated music sheet 30. The music sheet travels over an eccentrically pivoted rocking bridge 34, and the rocking fingers 37, which tend to move with the contact fingers in the direction to cause the contact fingers 32 to engage the bar 31, are supported each by means of a trailing point 38 which engages the sheet on the line of its support by the bridge 34, and the bridge 34 is provided with annular grooves 35 which correspond in position with the trailing points 38, so that when a perforation in the sheet comes beneath a trailing point, the point will be allowed to project through the sheet into the groove in the bridge 34, thereby permitting the rocking finger 37 to make the required movement for effecting the engagement of its corresponding contact finger with the bar 31. 50 The connections from the contact fingers 32 to the key operating magnets 3 are through a series of adjustable resistance devices. As shown, each of the contact fingers from which connection is made to one of the key operating magnets connects with a resistance coil 40 from which connection is made by one of a series of adjustable contact terminals 41 to the wire leading to the key operating magnet. The contact terminals 41 are formed by rods carried by a movable bar

200 and insulated from each other, as by making the bar 200 of suitable insulating material. The resistance coils 40 are also insulated from each other, and the connection between the contact finger 32 and the rocking fingers 37 is such as to avoid electrical connection between these parts, as by having the ends of the contact fingers inserted in suitable socket pieces 39 of insulating material carried by the rocking 75 fingers. As before stated, the bar 200 which carries the contact terminals 41 is movable, and this is for the purpose of moving the ends of the contact terminals or rods 41 over the resistance coils 40 so as to simultaneously change the resistance of all the branch circuits leading to the key operating magnets, thus providing means for changing or adjusting the effective strength of all such magnets to which circuit may be completed by engagement of their corresponding contact fingers 32 with the contact bar 31. To provide for the desired movement of the bar 200, it is shown as arranged to be moved by a pair of rocking arms 201 extending from a rock shaft 202 which is rocked through an arm 203 by a longitudinally movable operating rod 204. The rod 204 is provided with a suitable hand piece 162, or may be otherwise connected so as to permit of manual 95 movement of the bar 200 and corresponding adjustment of the resistance in the circuits to the key operating magnets when desired. Means are also provided for automatically shifting the bar 200 for controlling the resistance in the circuits to the key operating magnets, a plurality of resistance or expression controlling magnets, the circuits to which are controlled by the music sheet, being provided for this purpose. As shown, 105 three such magnets, F, FM and P are provided for causing the bar 200 and contact terminals or rods 41 to be moved to the positions of minimum resistance, medium resistance and maximum resistance, respectively. These magnets are shown as of the two-pole form with rotary armatures similar to the key operating magnets, their armatures being connected with the operating rod 204, the connection between the armatures 115 and the rod 204 being such that when the magnet F is energized the movement of its armature will cause the bar 200 and contact rods 41 to be shifted to the position shown in which the resistance coils 40 are practically or entirely cut out of the key operating circuits, and when the magnet FM is energized, the other two magnets being dead, the movement of its armature will cause the bar 200 and contact rods 41 to be shifted to an intermediate position, and when the magnet P is energized, the magnets F and FM being dead, the movement of its armature will cause the bar 200 and contact rods 41 to be shifted to the position in which all or prac- 120 125 130

tically all of each resistance coil will be inserted in its corresponding circuit. The circuits to these magnets F, FM and P are controlled by three of the contact fingers 32, 5 which in turn are controlled by suitably placed perforations in the music sheet 30. The magnets are connected with a positive pole of the battery 10 through wire c and each of the magnets is connected with one 10 of the contact rods 41 by a wire d. As there is no necessity of providing a variable resistance in these circuits, no resistance coils are provided between the contact rods with which the wires d connect and their corresponding contact fingers 32, the ends of the 15 rods, which for uniformity are carried by the bar 200, making sliding contact with suitable contact blocks 40' occupying the same relative position with relation to these 20 contact rods and the corresponding contact fingers as the resistance coils 40 occupy with relation to the contact rods and contact fingers connected in the circuits to the key operating magnets. From the section GenC of 25 the contact bar 31 with which the contact fingers 32 for the magnets F, FM and P make contact connection is made with the negative pole of the battery through a wire e and suitable connections hereinafter described. Pedal operating magnets LP and 30 SP are also provided and connected in circuits including contact fingers of the transmitting or controlling mechanism for affording automatic control of the pedals by 35 means of suitably placed perforations in the music sheet. These magnets are also shown as of the two-pole type, the pivoted armatures 21 of which are respectively connected with the loud and soft pedal devices of the 40 piano. The magnet LP is connected with the positive pole of the battery, as shown, through the wire e and is also connected by a wire f with two of the contact fingers 32, such connection being through the corresponding two contact rods 41 which, as in 45 the case of the connection for the resistance controlling magnets, engage suitable contact blocks 40' in place of the resistance coils provided for the key operating circuits. 50 The magnet SP is similarly connected with the positive pole of the battery by wire e', and by wire f' with two of the contact fingers 32 through their corresponding contact rods 41 the ends of which are in sliding contact with blocks 40'. From the section 55 PC of the contact bar 31 with which the contact fingers 32 for the magnets SP and LP make contact, connection is made with the negative pole of the battery through the wire e' and suitable connections hereinafter 60 described. The connection of each of the pedal operating magnets with two of the contact fingers 32 permits of the control of each of these magnets by perforations in 65 either one of two lines in the music sheet, and this is of great advantage in case either pedal is to be held in operative position for a considerable length of time, since it avoids the necessity of forming a correspondingly long perforation in the music sheet and enables the desired result to be secured by a 70 succession of shorter perforations alternately placed in the two lines of the music sheet corresponding to the two contact fingers which control the pedal magnet circuit. 75 The weakening of the sheet which would result from the presence of a very long perforation therein is thus avoided. To provide for manual control of the pedal operating magnets, connection is made from the wires 80 f and f' by wires g and g' respectively, to suitable finger keys or push buttons LPB and SPB from which connection is made back to the battery as before. The wire e from the sections GenC and PC of the contact bar 31 leads to a switch GenX from which connection is made to the common return wire h. This switch thus serves to put into or out of operation the devices for automatically controlling the means for varying 85 the resistance in the key operating circuits and for automatically controlling the circuits to the pedal operating magnets, that is, this switch controls what may be termed the "general expression controlling devices" of 90 the playing apparatus. The push buttons LPB and SPB also connect with the return wire h, and this wire and return wire b from the key operating magnets, connect with a wire i which leads to an automatic circuit 100 breaking device 55 from which wire i' connects to the main switch 139 from which a wire k leads to the negative pole of the battery. 105 The purpose of the circuit breaker 55 is to automatically open the circuits of the key operating magnets, pedal magnets and expression controlling magnets when the sheet approaches the end of its run, the circuit breaker being for this purpose controlled by 110 a suitably placed perforation in the music sheet. As shown, this circuit breaker consists of two contact terminals 5 and 6, which are normally in contact during the operation of the apparatus, and one of which, 6, 115 is under spring tension to move away from the other and is pressed into contact therewith by an arm 66 extending from an operating member 64 mounted on the shaft of the rocking bridge 34 as shown in the diagram. 120 The member 64 and arm 66 are held in the position shown by the armature 56 of a magnet TM, these parts being as shown and fully described in said Patent No. 753,809. This trip magnet TM is connected with the supply wire c by a wire l, and is connected by wire l' with one of the contact fingers 32 through the corresponding contact rod 41 and contact block 40'. This contact finger 125 is adapted to engage a section TC of the 130

contact bar 31 which is connected with the wire *i* leading to the circuit breaker 55 from which connection is made back to the battery as before described. This contact finger 5 which is included in the circuit to the trip magnet is held out of engagement with the section TC of the contact bar during the playing operation of the apparatus, but when the music sheet reaches the end of its 10 run, or when all of the perforations therein for controlling the circuits of the key operating magnets have passed the trailing points 38, a perforation comes beneath the trailing point corresponding to this contact 15 finger, thereby causing the engagement of this contact finger with the section TC to close the circuit to the trip magnet, whereupon the movement of the armature 56 releases the arm 66 permitting the bridge 34, 20 member 64 and arm 66 to rotate as described in said Patent No. 753,809, and the contact terminal 6 of the circuit breaker being thus permitted to move away from the terminal 5, the common return circuit is opened 25 at this point and further energizing of the key operating magnets, pedal magnets and expression controlling magnets prevented.

The motor by which the winding and re-winding rolls for the music sheet are driven 30 is represented at 134, the connection of the motor in circuit with the battery being by wires *c* and *s* leading from a positive pole of the battery to the motor and from the motor by wires *t* and *i'* to the main switch 35 139 and thence back to the battery by wire *k*.

The apparatus as thus far described is substantially similar in its operation to that shown and described in said Patent No. 753,809, differing therefrom mainly in the 40 use of the sectional contact bar 31, the purpose of which will be hereinafter described, instead of the single piece contact bar of the patent; in the arrangement of the resistance varying means for the key operating 45 circuits so that the resistance coils are stationary and the contact rods or terminals are moved relatively thereto, instead of having the resistance coils move, as in the patent; in having double contact finger connections for each of the pedal operating 50 circuits; and in the substitution of a switch for breaking the circuit connection to the general expression controlling and pedal operating magnets, in place of the mechanical 55 means shown in the patent for preventing the closing of the circuits to these magnets by their corresponding contact fingers.

The additional features and arrangements of parts and electrical connections shown 60 and which serve to provide expression controlling means for the emphasizing of individual notes and also for a supplemental general expression control, will now be described.

65 The key-operating magnets 3 are grouped

together by means of their operating circuit connections according to the consonance of the tones produced through the operation of the piano keys to which such magnets are connected, that is, magnets corresponding to tone producing devices for producing tones of the same note name form a group, those corresponding to tones of another note name form another group, and so on. The magnets for operating the A 70 keys form one group, those for operating the A# keys another group, those for operating the B keys another group, and so on, all the magnets for the entire keyboard being thus connected in twelve groups, each 75 group corresponding to the series of tones of the same name which are produced through the action of the correspondingly named finger keys. The connection of the key operating magnets in separate groups 80 is effected, as shown for the magnets for the A keys and the A# keys, by connecting the magnets of each group with adjoining or neighboring contact rods and contact fingers 85 32 of the transmitting or controlling mechanism, and providing a separate section of the contact bar 31 for each group or section of the series of contact fingers 32, each of such sections of the contact bar being connected to a circuit controlling 90 switch by which the electromotive force of the current supplied to the group of branch circuits including such section of the contact bar and its corresponding contact fingers and magnets may be varied. As shown, for 95 example, the magnets for operating the A keys are each connected by a wire *a* with one of the group of contact fingers 32 formed by the first eight at the extreme left hand end of the transmitting or controlling mechanism as shown in the diagram, such connection being made through the corresponding contact rods 41 and 100 resistance coils 40. This group of eight contact fingers make contact with a section AC 105 of the contact bar 31. In a similar manner the eight magnets for operating the A# keys of the piano are connected by wires *a'* with a second group of eight contact fingers 110 adapted to make contact with a section A#C of the contact bar 31; and similar connections will be made from each group 115 of key operating magnets corresponding to the differently named keys of the piano, to a group of the proper number of contact 120 fingers arranged together to make contact with a section of the contact bar. The contact bar section AC is connected by a wire *m* with an electrically operated circuit controlling switch AX through which connection is made to one or the other of two wires *n* and *n'* which connect with a source 125 of electrical energy, the wires *n'* supplying current of a higher voltage than is supplied by wire *n*. Similarly, the contact section 130

A#C is connected by a wire m' with an electrically operated circuit controlling switch A#X through which connection is made with one or the other of the supply wires n and n' . Similar connections and circuit controlling switches will be provided for the sections of the contact-bar corresponding to the ten remaining groups of key operating magnets.

10 The supply wires n and n' instead of being connected directly with the battery or other source of electrical energy are, for the purpose of providing means for changing the electromotive force of the current supplied to all of the key operating circuits, connected with the battery through an electrically operated double circuit controlling switch AL. This switch AL as shown comprises a pair of connecting plates al and al' mounted on a pivoted disk 205 of fiber or other insulating material. The wires n and n' connect through suitable contact terminals with the plates al and al' respectively, and the plate al , when the carrying disk is in the 25 position shown, is connected with a positive pole of the battery 10 through the wire c' and a branch wire c^2 connecting with the plate al through a suitable contact terminal. Through this connection the lowest voltage 30 current is supplied to the operating magnets, such current being, for example, an eight volt current. The connecting plate al' , when the disk is in the position shown, is connected by a wire c^3 with a pole of the 35 battery for supplying, for example, a ten volt current to the key operating magnets through the wire n' . When the carrying disk 205 is shifted in the direction of the arrow, the plate al is moved out of engagement with the contact terminal of the wire c^2 and into engagement with the contact terminal of the wire c^3 so as to form a connection for supplying a ten volt current through the wire n , and the plate al' then 40 connects with the contact terminal of a wire c^4 leading to a twelve volt, for example, terminal of the battery 10, thereby making connection for supplying a twelve volt current through the wire n' . By shifting the 45 switch AL, therefore, in the example shown, the current supplied through the wires n and n' may be changed from eight and ten volts respectively to ten and twelve volts respectively, or vice versa, and this change 50 will of course affect all the key operating magnets to which circuit may be completed. This switch AL and the means for operating it hereinafter described thus form a supplemental general expression controlling 55 means, while the series of switches AX, &c., with the operating means therefor herein-after described provide for what may be termed a group expression control which enables individual tones to be emphasized 60 in the manner before pointed out.

The circuit-controlling switch AX for controlling the circuits to the group of key operating magnets for operating the A keys is automatically controlled by means of one of the contact fingers 32 which makes contact with an individual section ANC of the contact bar 31, said contact finger and contact being connected in a circuit leading through the magnet of said controlling switch as follows:—starting from the battery 10 by wire c' to the switch magnet and thence by wire o to one of the contact rods 41, contact block 40', contact finger 32 to contact ANC and thence by wire p through a switch GX to the return wire h and by wire l , circuit breaker 55 and wire l' to main switch 130, and thence by wire k back to the battery. When the magnet of the controlling switch AX is dead, the connecting plate al of the switch rests in the position shown in the diagram to connect wire n from the section AC of the contact bar with wire n for supplying the low voltage current to the key operating magnets of the "A" group. When the contact finger engages the contact section ANC, however, to energize the switch magnet, the connecting plate al is shifted to connect the wire m with the wire n' for supplying the higher voltage current to the key operating magnets of this group. The circuit controlling switch A#X for changing the electromotive force of the current impressed on the circuits of the magnets for operating the A# keys is similarly connected with the supply wire c' and by wire c' and one of the terminal rods 41 and contact blocks 40' with a contact finger 32 which makes contact with an individual contact section A#NC which is connected with the return wire p , from which connection is made through the switch GX back to the battery as before pointed out. The connecting plate of this controlling switch A#X normally rests in the position shown in the diagram for connecting the contact section A#C with the low voltage supply line n , and when the switch magnet is energized its connecting plate is shifted to connect the contact section A#C with the higher voltage line n' . Similar connections will be made for automatic control of the circuit controlling switches for the operating circuits for the remaining groups of key operating magnets, and through such connections the circuit controlling switches AX and A#X, &c., will be automatically controlled by the music sheet through perforations suitably placed so that when any particular tone is to be emphasized the contact finger 32 corresponding to the controlling switch for the circuits to the group of magnets for operating the keys corresponding in name to the tone to be emphasized will be operated to close the circuit for operating 120

such switch, and the section of the contact bar 31 corresponding to such group of key operating magnets will thereby be connected with the higher voltage wire n' and a current of increased electromotive force thereby supplied to the magnet or magnets in that particular group to which circuit is completed through their contact fingers 32. The shifting of the controlling switch, AX or A#X, etc., for the operating circuits of each of the groups of the key operating magnets thus changes the potential strength of action of the magnets of the group by changing the electromotive force available for energizing each magnet of the group, and this change in the available electromotive force and corresponding change in the potential strength of action of the magnets is secured without causing any, or substantially any, delay or acceleration in the rising of the current in the operating circuit to its full operating value, and therefore, without affecting the delay of the operation of the magnets or tone producing devices.

25 As the several contact sections AXC and A#NC, etc., will be connected with a common return wire p , the contact fingers corresponding to such contact sections might be grouped together and a single contact section substituted for the several individual contact sections, as will be readily understood.

30 Manual control of the circuit controlling switches AX and A#X is provided by means of push buttons or finger keys AB and A#B connected between the wires ϕ and ϕ' respectively and the return wire h by wires q and q' so that by means of either of these push buttons circuit may be closed to the corresponding circuit controlling switch for raising the voltage of the current supplied to the corresponding group of key operating magnets. Similar finger keys and connections will be provided for the controlling switches corresponding to the remaining groups of circuits and key operating magnets with which the instrument will be provided. The switch GX serves to cut out the contact fingers and contact sections through the operation of which the circuit controlling switches AX, etc., are automatically controlled.

35 The double circuit controlling switch AL for changing the voltage of the current supplied through the wires n and n' is automatically controlled by the music sheet, being for this purpose connected with one of the contact fingers 32 which makes contact with a section ALC of the contact bar 31. When this contact section ALC is engaged by its corresponding contact finger 32 and the switch GX is closed, circuit will be completed through the magnet of the switch AL as follows:—starting from the battery 40 by wire c' to the switch magnet, thence

5 by wire r to one of the contact rods 41 and its corresponding block 40' and contact finger 32 to contact ALC, and thence by wire p to switch GX and by wires h , i , contact breaker 55, wire ϕ' , main switch 139, and wire k , back to the battery. The switch AL normally rests in the position shown in the diagram, in which the wire n is connected with the eight volt pole of the battery and the wire n' with the ten volt pole. 70 When the switch magnet is energized, however, the carrying disk 205 is shifted to connect the wire n with the ten volt pole of the battery and wire n' with the twelve volt pole of the battery in the manner hereinbefore pointed out. Manual control of this switch is provided by means of a finger key or push button ALB connected by wire s between the wire r and return wire h so that by closing the circuit at this push button 75 the circuit will be completed to the switch magnet independently of the automatic circuit controlling means.

80 The connection of the operating magnets in groups each of which contains the magnets corresponding to tone producing devices for producing tones of the same note name, by connecting the circuits for each group of magnets so as to be controlled by a group of adjacent devices of the transmitting or controlling mechanism, is of advantage independently of the expression control resulting therefrom, in that the perforations in the music sheet for controlling the operation of the transmitting or controlling mechanism will usually be more evenly distributed transversely of the sheet than is the case with sheets which are perforated for use with the old style of controlling or operating mechanism where the devices with which the perforations co-act are arranged in order corresponding to the succession of tones in the musical scale. This advantage of an improvement in the music sheet resulting from arranging the devices of the controlling mechanism which co-operate with the perforations in the music sheet in successive groups, each group containing devices corresponding to tones of the same note name, is not peculiar to a controlling 90 mechanism of the form shown in Figs. 1 and 1^a, but applies to perforated music sheets intended for use with any form of controlling mechanism in which the devices for co-operating with the perforations of the music sheet are arranged so that the devices corresponding to tone producing devices for producing tones of the same note name will be together. An example of the difference in the arrangement of the perforations in a 95 music sheet such as now commonly in use and intended for a controlling mechanism in which the devices for co-operating with the perforations of the sheet are arranged in order corresponding to the successive tones 100 105 110 115 120 125 130

of the musical scale, and a sheet intended for use with a controlling mechanism in which the devices for co-acting with the perforations of the sheet are arranged in successive groups, each group containing devices corresponding to tones of the same note name, is illustrated by Figs. 2 and 3. Fig. 2 representing a portion of a sheet such as last referred to, and Fig. 3 representing the corresponding portion of a sheet such as heretofore commonly in use for causing the production of the same music. The music represented by the perforations in the sheet shown in Figs. 2 and 3 is shown in ordinary musical notation below these figures. It will be seen that the perforations in Fig. 2 are much more evenly distributed transversely of the sheet than in Fig. 3, and this better distribution of the perforations avoids the weakening of the sheet which frequently results from perforations being located closely together, as shown in Fig. 3, and avoids liability of the sheet becoming crumpled or bent on a line of successive perforations, and also avoids liability of uneven stretching of the sheet due to bunching of the perforations near one edge of the sheet while the portions of the sheet near the other edge are left free from perforations.

It will also be understood that while the invention relates more especially to electrically operated automatic playing apparatus for musical instruments, yet some features of the invention, considered both from its method and apparatus side, are not to be limited to such electrically operated playing apparatus, but apply generally to other forms of musical instruments and playing apparatus therefor.

What is claimed is:—

1. A musical instrument, comprising, in combination, actuating devices, means to group the actuating devices of the instrument into groups of the same note-name, and means to automatically simultaneously increase the strength of action of all of the groups of actuating devices.
2. An electrically - operated automatic playing musical instrument, comprising, in combination, means to group the tone-producing devices of the instrument into groups, each group of which contains tone-producing devices of the same note name, an operating magnet for each tone-producing device, controlling means for each group to vary the strength of current in the operating magnets, a source of electrical energy, and connections therefrom to the operating magnets and the controlling means.
3. An electrically-operated musical instrument, comprising, in combination, connections to group the tone-producing devices of the instrument into groups of the same note-name, a source of electrical energy, connections therefrom to the groups,

independent automatically-operated expression-controlling means in the connections to each group to vary the voltage of the current delivered to each group.

4. An electrically-operated playing apparatus for musical instruments, comprising, in combination, a plurality of magnets, each of which is connected to operate a tone producing device of the instrument, connections to group the magnets which operate the tone-producing devices of the same note name, a plurality of switch devices each of which controls the strength of operation of one of said groups of said magnets by varying the voltage of the current delivered to the groups, a source of electrical energy, and connections therefrom to the magnets of said groups and said controlling devices.

5. An electrically-operated musical instrument, comprising the combination of tone-actuating devices, connections to group the tone-actuating devices of the instrument into groups of the same note-name, a source of electrical energy, connections therefrom to the group connections, independent automatically - operated expression - controlling means in the connections to each of the group connections to vary the voltage of the current delivered to each of the tone actuating devices of each group whereby the expression of the tone in the groups may be varied.

6. An electrically-operated musical instrument, comprising connections to group the tone-producing devices of the instrument into groups of the same note-name, magnets to operate the tone-producing devices, a source of electrical energy, electrical connections between each one of the magnets of said groups and the source of electrical energy and connected at different potential points of the source of electrical energy, means to shift the connections to the source of electrical energy to vary the current in each group, and a note-sheet to control the action of said shifting means, whereby the expression produced by the tone-producing devices in each group may be varied.

7. An electrically-operated musical instrument, comprising the combination of tone-actuating devices, connections to group the tone-actuating devices of the instrument into groups each including tone-actuating devices of the same note-name, an operating magnet for each tone-actuating device, a resistance in each connection, a device to independently control the voltage for each group, means to simultaneously vary the resistance in each connection to each group, a general expression double-circuit controlling device to vary the strength of current in the independent voltage-controlling devices, a source of electrical energy, and connections from the source of energy at different potential points to the operating magnets and to

the independent voltage-controlling devices for each group, and a note-sheet, the perforations therein operating said controlling devices.

5. An electrically-operated piano-player, comprising a plurality of groups of electrically-operated key-actuating devices, automatic means to simultaneously change the voltage of the current supplied to all of the groups of said actuating devices, means to effect the automatic operation of the voltage-changing means, a source of electrical energy, and connections at different potential points thereof and to the key-actuating devices and said automatic voltage-changing means.

9. An electrically-operated piano-player, comprising the combination of key-operating devices, electrical connections to group together said devices which actuate tone-producing devices of the same note-name, a source of electrical energy, switch means to automatically change the strength of current supplied to all of the key-operating devices of each group to increase the strength of action of each individual key-actuating device in each group, means comprising a perforated note-sheet to cause the operation of said automatic current-changing means, and connections from different potential points of the source of energy to said switch means, as described.

10. An electrically-operated musical instrument, comprising in combination, electro-magnetic devices to actuate the tone-producing devices of the instrument, means to connect said devices together into groups of the same note name, a plurality of voltage-controlling switches to vary the magnetic strength of action of said devices, a double-circuit controlling switch to control the voltage of the current supplied to the plurality of voltage controlling switches, a source of electrical energy, and connections therefrom at different potential points to the voltage-controlling switches and the double-circuit controlling switch.

11. An automatic playing apparatus for musical instruments, comprising a plurality of key-operating devices grouped to actuate the tone-producing devices of the same note-name, means to support and feed a music sheet, contact means controlled by the music sheet to cause the key-operating devices to operate, a plurality of voltage-controlling devices each to control the strength of action of a group of key-operating devices, and electro-magnetic means controlled by the music sheet to control the operation of plurality of voltage-controlling devices, a source of electrical energy, and connections therefrom at different potential points to the plurality of voltage-controlling devices.

12. An electrically-operated playing apparatus for musical instruments, comprising

groups of magnets, the magnets of each group actuating tone-producing devices of the same note-name, branch connections to said magnets, means to supply electrical energy to said connections, a plurality of current-controlling devices, one for each of said groups, each of which controls the strength of action of said magnets by varying the strength of current available for energizing each magnet of the group, a source of electrical energy, and connections therefrom to the branch connections and the current-controlling devices.

13. The combination in a musical instrument, of a plurality of magnets grouped to cause the operation of tone-producing devices of the same note-name, branch connections for said magnets, and means for supplying electrical energy to said connections, a plurality of voltage-controlling devices one for each of said groups of said magnets which causes the operation of tones of the same note-name, and a general expression voltage-controlling device to simultaneously effect an increase or decrease in the voltage of the current supplied to said controlling devices, a source of electrical energy, and connections therefrom to the branch connections and to the plurality of voltage-controlling devices.

14. An electrically-operated playing apparatus for musical instruments, comprising electrically-operated devices which actuate the tone-producing devices of the instrument, branch connections for the devices to group the tone producing devices of the same note-name together, a resistance device in each of said connections, means to vary all of the resistances simultaneously, a plurality of voltage controlling devices each of which controls a group of said branch connections to determine the voltage of the current supplied to any one or more of the branch circuits of the group that may be closed, a source of electrical energy, and connections therefrom to the operating devices and the current controlling devices.

15. In an electrically-operated playing apparatus for musical instruments, the combination, of electrical devices which actuate the tone-producing devices of the instrument, connections thereto arranged in groups of the same note-name, means to support and feed a music sheet, and a circuit-closer in each of said connections adapted to be controlled by the music sheet, a resistance device in each of said connections, means controlled by the music sheet to vary the resistances simultaneously, a plurality of controlling devices, one of which controls a group of connections to vary the voltage of the current which will be supplied to any one or more of the circuits of the group that may be closed, and a circuit-closer in each of said connections controlled by the music sheet to operate said controlling de-

- 5 vices, a general controlling device to effect a general increase or decrease in the voltage of the current transmitted to the operating connections, and means controlled by the music sheet to operate said general controlling device.
16. An automatic playing apparatus for musical instruments, comprising, in combination, a plurality of electrical operating devices to operate the tone-producing devices of the instrument, means to connect the devices in groups each of which contains operating devices that cause the production of tones of the same note name, a general expression-controlling device and group expression - controlling means comprising a plurality of controlling devices each of which controls the strength of action of a group of said operating devices that actuate tone-producing devices of the same note-name by varying the amount of energy directly available to cause each key-operating device of the group to operate.
17. A musical instrument comprising, in combination, electrical key - operating devices to actuate the tone-producing devices of the instrument, branch connections therefor to group said devices to produce tones of the same note names, a general expression-controlling means to vary the resistance of the key-operating connections, and group expression - controlling means comprising a group of magnets, each one of which controls the strength of action of a group of key-operating devices which actuate the tone-producing devices of the same note-name by varying the voltage of the current delivered to the key-operating circuits, a source of electrical energy, and connections therefrom to the key-operating devices, the branch connections, the expression-controlling means, and the operating devices.
18. An electrically - operated automatic playing apparatus for musical instruments, comprising in combination a plurality of electrically - operated devices, connections therefor arranged in groups, a resistance in each of the connections, a general expression-controlling means to vary the resistance of said operated devices, group expression - controlling means to control the strength of action of the operating devices in said groups, each group including only devices which cause the production of tones of the same note-name, and a second general expression-controlling means to effect a general increase or decrease of the voltage of the current transmitted to the operating connections, a source of electrical energy and connections from different potential points to said operated devices, the general expression-controlling means, the group expression-controlling means, and the second expression-controlling means.
19. An electrically-operated playing apparatus for musical instruments, comprising a series of operating magnets, circuits for said magnets, arranged in groups which cause the production of tones of the same note name; means to support and feed a music sheet, a circuit closer in each of said circuits to be controlled by the music sheet, the circuit closers for the circuits to said magnets that cause the production of tones of the same note-name being located in adjacent positions, a sectional contact bar having a separate section for each of said groups of circuits, and means to control the electrical connection to each of said contact sections to vary the strength of current in the magnet circuits including such section.
20. In an automatic-playing musical instrument, the combination, of devices to actuate the tone-producing devices of the instrument, circuit-closing devices grouped into sections and electrically connected to the devices which actuate tone-producing devices of the same note-name, a resistance in each connection, means to simultaneously vary the resistance in each connection of the tone-actuating devices, means to control the voltage of each of the sections, a switch-device to vary the general expression of the tone-producing devices, a source of electrical energy, connections to the tone-actuating devices and circuit-closing devices, a return circuit from the actuating devices, and means including a trip-magnet in the return circuit to open the same at the end of the piece being played, substantially as described.
21. A musical instrument, comprising, in combination, electrical connections to group the tone producing devices into groups of the same note-name, an expression-controlling switch device for the tone-producing devices of each group, a general expression-controlling switch device for all of the said group-controlling devices, a source of electrical energy, electrical connections from the source of electrical energy to the groups of tone-producing devices, said group controlling switch devices, and the general expression-controlling switch device to supply electric current to the individual tone-producing device of each group.
22. A musical instrument, comprising connections to group the tone-actuating devices into groups of the same note-name, a source of electrical energy, a switch-controlling device for the tone-actuating devices of each group to supply electrical energy of normal voltage to the actuating devices, connections from the source of energy to the controlling device of each group, a general electrical energy-controlling device to control the voltage supplied to all of the said switch controlling devices

to vary the electrical energy supplied thereto, and connections from the source of energy to the general electrical energy-controlling devices, the switch controlling devices and to the tone-actuating devices, as described.

23. In an electrically-operated musical instrument, the combination, of a contact bar divided into sections, operating magnets to 0 actuate the tone producing devices, electrical connections from each section thereof to the operating magnets of the instrument which sound tones of the same note-name, means to normally supply electrical energy 15 at a certain normal voltage to said sectionally-divided contact bar, means to vary the voltage of the current delivered to any section of said bar to vary the expression of one or more tones produced by the operating 20 devices during the operation of the instrument, a source of electrical energy, and electrical connections therefrom to the operating magnets, switch-changing means and contact bar.
24. In an electrically-operated piano-player, a source of electrical energy, key-actuating devices, connections from said devices to different potential points of the 25 source of electrical energy, an electro-magnetic switch device in the connections to 30 change the voltage of the current supplied to the key-actuating devices by opening one of said connections and closing another, and

a perforated note sheet for controlling the operation of the switch-device. 35

25. An electrically-operated piano-player, comprising electrically-operated actuating devices, a source of electrical energy, connections between said devices and different potential points of the source of electrical 40 energy, a single electro-magnetic switch device designed to close one of said connections and open another to vary the current supplied to the actuating devices, circuit closing devices for the actuating devices 45 and means comprising a note-sheet to cause the operation of the circuit-closing devices and said switch device.

26. In an electrically-operated piano-player, a source of electrical energy, key-actuating devices, connections from said devices to different potential points of the source of electrical energy, a single electro-magnetic switch device in the connections 50 to change the voltage of the current supplied to the key-actuating devices, and controlling means to cause the operation of the switch-device.

In testimony whereof, I have hereunto set my hand, in the presence of two 55 sub-scribing witnesses.

JOHN F. KELLY.
